UNITED STATES PATENT OFFICE.

JOSEPH LE ROY PARKINSON, OF CAMBRIA, WISCONSIN.

SEWING-MACHINE WORK-BASKET.

SPECIFICATION forming part of Letters Patent No. 252,695, dated January 24, 1882.

Application filed May 5, 1881. (Model.)

To all whom it may concern:

Be it known that I, JOSEPH LE ROY PARKINSON, of Cambria, in the county of Columbia and State of Wisconsin, have invented a new 5 and useful Improvement in Sewing-Machine Work-Baskets, of which the following is a full, clear, and exact description.

The object of my invention is the production of a convenient work-basket attachment for 10 sewing-machine tables.

In the accompanying drawings, Figure 1 is a perspective view of a sewing-machine table having my invention attached; and Fig. 2 is a cross-section of the same, having a portion 15 broken away.

Similar letters of reference indicate corresponding parts.

The basket or work-receptacle A, which may be of any size and made of any suitable material, is secured by screws or any other suitable means to the inside of the board or wing B, which board or wing is provided at its upper and lower corners with the perforated metal plates a a', through which the headed screw 25 rod or bolt b passes for hinging the board to the under side of the table, as shown in the drawings. The end of the board or wing is cut away or guttered out, so as to inclose and conceal the bolt b when in place, (or a hole might 30 be made through the wing for this purpose,) and the end of the bolt screws into the plate c, which is secured in proper position to the under side of the table D of the sewing-machine. The lower edge of the board is sup-

ported on the lower end of the perforated 35 bracket C, through which perforation the bolt b passes before passing through the perforation in the plate a'. The upper end of the bracket C is screwed to the under side of the table, and serves also as a brace to hold the board 40 firmly in place. Secured to the board, above the basket, is the additional trough or receptacle E, intended for needles and spools of thread and similar articles.

When the device is attached to machines 45 already made which have side drawers I provide the side plate or brace, e, for giving the board additional support and strength. In new machines I propose to have a brace cast upon one of the legs of the machine for sup- 50 porting the wing.

Though I have shown no lock or catch for fastening the wing when closed, it is obvious that these devices may be provided and not depart from the spirit of my invention. 55

Having thus described my invention, what I claim as new, and desire to secure by Letters Patent, is—

The board or wing B, provided with the receptacles A and E, and provided with the perforated corner-plates a a', in combination with the bracket C, screw-plate e, and screw bolt or rod b, substantially as and for the purposes specified. 60

JOSEPH LE ROY PARKINSON.
